UNITED STATES PATENT OFFICE.

ENEL GODLOVE, OF AMISTAD, NEW MEXICO.

GAS AND SPARK LEVER FOR THE CONTROL OF MOTOR-VEHICLE ENGINES.

1,303,653.

Specification of Letters Patent.

Patented May 13, 1919.

Application filed January 3, 1919. Serial No. 269,473.

To all whom it may concern:

Be it known that I, ENEL GODLOVE, citizen of the United States, residing at Amistad, in the county of Union and State of

5 New Mexico, have invented certain new and useful Improvements in Gas and Spark Levers for the Control of Motor-Vehicle Engines, of which the following is a specification, reference being had therein to the

10 accompanying drawing.

This invention relates to gas and spark levers for the control of motor vehicle engines, and has for its primary object the provision of an attachment adapted to be 15 readily affixed to one of a pair of oppositely projecting levers to constitute an operating extension of the same disposed in close relation to the other of said levers whereby both levers are easily accessible to and may be

20 operated by one hand.

In some types of automobiles, a common 25 illustration of which is the well known Ford car, the spark and throttle levers project in opposite directions from the steering post so that one of said levers is adjusted by the right hand of the operator, so to speak, while the other lever is adjusted by the left hand.

As a result of the war, it has become a 30 necessity to overcome this widely spaced relation of the spark and throttle levers to enable both of said levers to be adjusted by one handed or one armed persons.

The present invention involves a conception 35 of an exceedingly simple and inexpensive attachment, quickly applied, and capable of converting the oppositely and widely separated levers into the above stated closely related levers arranged at the same side of 40 the steering post. The attachment may be applied to the throttle lever or to the spark lever with equal facility dependent upon whether the operator is right handed or left handed.

45 With the foregoing in mind, the invention may be readily understood from the detail description hereinafter contained when read in connection with the accompanying drawings forming part hereof, in which latter 50 the preferred embodiment of the invention is illustrated.

In the drawings:

Figure 1 is a detail view of the attachment before its application;

55 Fig. 2 is a perspective view of the steering

post and wheel, with associated parts, showing the application of the attachment to the spark lever; and

Fig. 3 is a horizontal sectional view.

Referring more specifically to the drawings wherein like reference letters refer to the same parts in the several views, A represents the steering post of an automobile, and B the steering wheel at the upper end thereof. C is the spark lever and D the throttle lever mounted to control the parts connected therewith (not necessary to illustrate) in the usual manner, to obtain the desired feeding and operating of the motor. The spark and throttle levers are respectively adjusted over and secured in adjusted 60 positions on the toothed quadrants c and d mounted in fixed position independently of but adjacent to the steering wheel B, 65 conveniently below the same.

70 That much of the construction thus far described is old in the art, and it will be appreciated that the spark lever C is customarily adjusted by the left hand of the user while the throttle lever D projecting away 75 from the opposite side of the steering post, is adjusted by the right hand of the user, or vice versa. With this understanding, my present invention consists of an attachment removable in character, transferable from 80 either the spark lever C or the throttle lever D to the other of said levers, at will, said attachment to constitute an extension of the 85 lever to which it is secured running to a position alongside of the oppositely projecting 90 lever. For illustration, E represents a lever operating handle or extension occupying a position approximately parallel to the throttle lever D at the right of the steering post A. This handle extension at its inner or 95 left hand end passes around the front of the steering post, or its casing (for present purposes they may be regarded as a unit), and thence rearwardly at the left of the steering post to constitute an angular or offset end F, 100

the same carrying a detachable clamp G of suitable form to embrace and be bound by the screws or bolts g to the spark lever C. A reversal of this arrangement would effect the securing of the offset end F of the lever 105 extension E to the opposite or throttle lever D, thereby bringing the lever extension to the left of the steering post in parallel relation to the spark lever C. In either of these positions it will be observed that the lever 110

extension E and the throttle lever D, or on the other hand, the extension E and spark lever C, are caused to occupy a close relation at one and the same side of the steering post 5 where they may both be manipulated by the fingers of a single hand instead of requiring the use of both hands as formerly in the art.

It is believed that the foregoing device 10 will prove of great benefit to persons who have had a hand or arm injured or lost incident to the war or from other causes.

While I have herein illustrated one special embodiment of the invention, it will be apparent to persons skilled in the art to which 15 the invention relates, that the same is capable of embodiment in other forms and devices, as may be embraced within the terms of the hereto appended claims.

I claim:—

20 1. The combination with controlling means substantially as described including oppositely disposed adjustable control levers, of an attachment secured to one of said levers and extending to a position adjacent to the 25 other of said levers.

2. The combination with controlling means substantially as described including oppositely disposed adjustable control levers, of an attachment secured to one of said levers 30 and extending to a position adjacent to the other of said levers, the securing means for said attachment being detachable to enable reversing the position of the attachment so that the same may be secured to the other of 35 said levers to extend to a position adjacent to the lever to which it was first attached.

3. An attachment of the character described comprising a lever extension and means at the inner end thereof for securing 40 the same to a lever, such as a spark lever, to enable operation of said lever from a point

opposite to the direction in which the lever normally projects.

4. An attachment of the character described comprising a lever extension and means at the inner end thereof for securing the same to a lever, such as a spark lever, to enable operation of said lever from a point opposite to the direction in which the lever normally projects, the attaching end of said 50 lever extension being offset for the purpose set forth.

5. An attachment of the character described comprising a lever extension and means at the inner end thereof for securing the same to a lever, such as a spark lever, to enable operation of said lever from a point 55 opposite to the direction in which the lever normally projects, the securing means for said lever extension being detachable.

6. An attachment of the character described comprising a lever extension and means at the inner end thereof for securing the same to a lever, such as a spark lever, to enable operation of said lever from a point 65 opposite to the direction in which the lever normally projects, the attaching end of said lever extension being offset, and the securing means for said lever extension being detachable.

7. The combination with a controlling means, including oppositely disposed control levers, of a control means supplemental to one of said levers and extending to a position adjacent to the other of said levers.

In testimony whereof I hereunto affix my signature in the presence of two witnesses.

ENEL GODLOVE.
